UNITED STATES PATENT OFFICE.

FRANCIS STICKER, OF NEW YORK, N. Y., ASSIGNOR TO JULIUS C. DRUCKLIEB
AND CHARLES A. DRUCKLIEB, OF SAME PLACE.

STEAM-INJECTOR.

SPECIFICATION forming part of Letters Patent No. 645,273, dated March 13, 1900.

Application filed November 20, 1899. Serial No. 737,681. (Model.)

To all whom it may concern:

Be it known that I, FRANCIS STICKER, of New York, in the county of New York and State of New York, have invented certain new and useful Improvements in Steam-Injectors; and I do hereby declare the following to be a full, clear, and exact description of the invention, such as will enable others skilled in the art to which it appertains to make and use the same.

This invention contemplates certain new and useful improvements in steam-injectors, and is more particularly an improvement upon the double-jet machine shown and described in Letters Patent No. 600,454, issued to me March 8, 1898. By the device embraced by the patent mentioned the starting is effected by admitting steam to both sets of jets simultaneously and giving the first steam and water a chance of free escape to the atmosphere and insuring from the first issue of steam to the jets an intimate contact of steam and water, effecting the instant condensation of the steam in the forcer and prompt working of the device. I pointed out in that patent the advantages derived from preventing back pressure of steam of the forcer from retarding the operation of the lifter. I showed and described a wall in the discharge-chamber over which the water from the lifter would rise, completely submerging the combining-tube of the forcer and effecting the condensation of steam therein. The initiatory steam from the lifter was permitted to escape direct to the atmosphere, preferably through a port in the wall before mentioned, which port was choked as soon as water was lifted and discharged from the lifter. I also showed a single cock having two ports, one for the auxiliary and supplemental overflows of the lifter and the other for the primary overflow of the forcer. In this cock was a third port through which communication was established to the boiler after the overflows were closed.

The object of the present invention is to improve the starting facilities of the injector, as well as its general construction, the details, and arrangement of parts, by preserving the original design of simplicity and compactness, enabling the operation of the machine to be controlled by a single cock. It is contem-

plated by the present invention to provide additional and improved means for preventing back pressure in the discharge-chamber of the lifter occasioned by the escape of steam from the forcer, insuring a prompt entering into the combining-tube of the forcer of the water discharged by the lifter. It is also within the contemplation of my invention to provide the combining-tube of the forcer with an overflow-outlet for aiding in starting the injector, which will be tightly and positively closed after the machine is in operation, avoiding the use of so-called "automatic" valves, which in machines subject to high ranges of pressure are totally inadequate, for that they are normally held closed by a vacuum and are rendered inoperative when a pressure is present beneath them in place of the vacuum. A vacuum exists beneath such valves only during a very limited range of pressures and of very low water. In my injector I employ a positive device which is not affected by either vacuum or pressure and which will keep the several openings employed in the starting operation tightly and securely closed after the jet is once established.

The invention will be hereinafter fully set forth, and particularly pointed out in the claims.

In the accompanying drawings, Figure 1 is a vertical longitudinal sectional view of an injector constructed in accordance with the present improvement. Figs. 2 and 3 are side elevations at right angles to each other of the cock. Fig. 4 represents in series cross-sectional views taken through different points of the cock and showing the various positions thereof. Fig. 5 is a sectional detail view showing the embodiment in the present device of one of the features embraced by the before-mentioned patent.

Referring to the drawings, A designates the casing or casting; a, the steam-inlet; a', the steam-chamber; a², the water-inlet; a³, the boiler-outlet, and a⁴ the overflow-opening.

B designates the forcer, and C the lifter. The steam-jets 1 and 2 of the forcer and lifter, respectively, are made integral with the front caps 3 and 4, each of which is screwed into an opening in line with its complementary

series of tubes, both jets extending across the steam-chamber a' and having openings for the admission of steam. By thus forming the steam-jets integral with the front caps I am enabled to quickly remove the same, and thus provide for ready inspection of the interior of the casing, as well as for the removal of the series of tubes. The combining-tube 5 and delivery-tube 6 of the lifter are of ordinary construction, the latter tube opening into the discharge-chamber D. The combining-tube of the lifter is formed in two parts or sections 7 and 8. The part 7 has a cylindrical enlargement 9, which fits in an opening in a wall 10 within casing A and at its forward end is screwed into a second wall or partition 12. The section 8 of this combining-tube of the lifter forms part of the delivery-tube 13, which latter is screwed into an opening constituting a port 14, through which passes what is commonly called the "primary" overflow, as well as the established jet of steam and water. The cylindrical enlargement 9 of the combining-tube encircles and incloses the sectional part 8 of such tube. The bore of the forcing steam-jet being larger in area at its smallest diameter than the smallest cross-sectional area of the delivery-tube, more steam will be supplied in starting the injector than can find an outlet through this delivery-tube, and hence this surplus will spill at the inlet to the sectional portion 8 and passing into the enlargement 9 will from the latter enter a supplementary overflow passage-way 15, which terminates in the overflow-opening a^4 . In this way back pressure in the discharge-chamber D is entirely obviated, and in consequence a quick lift of water is effected. This being accomplished, the water rises within chamber D, encircling the combining-tube of the lifter, and passing over the wall 10 and around the enlargement 9 will escape through the auxiliary overflow passage-way 16, which opens into the overflow-opening a^4 . In thus causing the water to rise within the delivery-chamber D, as set out in my before-mentioned patent, immediate condensation of the steam within the tubes of the lifter is effected, and the water which surrounds the lifter combining-tube can at once enter the latter as condensation takes place.

E designates a single cock by which the operation of the machine is controlled. This cock, which is preferably of tapered formation, fits snugly within the bore of the overflow-opening a^4 and is held in place by a screw-plug b. On the outer end of the stem b' is an operating-handle b², by which the cock may be turned to the right or to the left. In the shell of the cock is a longitudinal slot b³, which is designed to communicate with the primary, supplemental, and auxiliary overflows for establishing communication between the latter and the opening a^4 . There are preferably two such openings b³ formed in diametrically-opposite lines in the cock,

so that the latter may be turned to the right or to the left and also to enable the boiler-connecting pipes to be drained. In my before-mentioned patent the port in the operating-cock for the primary overflow of the lifter was in comparison with the port for the overflows of the lifter of decidedly-greater area for the purpose of enabling the overflow of the lifter to be closed in advance of that of the lifter. In my present device the operating-cock is provided with a long tapered slot communicating with the several overflows; but to insure the correct operation of the machine the overflow-passages in the casing are of greater diameter than heretofore. Passing transversely through the cock E is a port d, through which the established jet passes to the boiler when the cock is so turned as to bring such port in line of communication between the delivery-tube 13 and the boiler-outlet a^3 . The primary overflow for the lifter is so arranged that even during the starting operation the opening through port d to the boiler is established, this opening becoming gradually larger and giving the established jet a chance to enter the boiler instead of escaping through the overflow. It will be seen by reference to the cross-sectional views of Fig. 4 that the established jet is free to pass to the boiler before the primary overflow of the lifter is fully closed, the auxiliary and supplemental overflows being closed from the time the port d is brought into line to receive the established jet, as shown in the third series of views, Fig. 4. Another advantage resultant from the present form of cock is that the injector and the communicating-pipes to the boiler are free to drain, as there is always an opening during the first part of the starting and stopping.

In Fig. 5 I have indicated in the wall 10 an escape-port e, similar to the port e', shown and described in my before-mentioned patent. This port, the purpose of which is to permit of the escape of the initiatory steam of the lifter, may be employed with like results and advantages as those set forth in my patent, the primary object of effecting the raising of the water within the delivery-chamber so as to submerge the combining-tube and pass over the wall being attained whether or not such escape-port be present.

In operation steam is admitted to the steam-chamber a' and will pass simultaneously through jets 1 and 2. The steam passing through the tubes of the lifter and into the chamber D and thence through the auxiliary overflow passage-way 16 will escape through the overflow-opening a^4 into the atmosphere, effecting the lifting of the water and the discharge thereof into chamber D. The steam entering through the steam-jet 1 of the lifter passes into the combining-tube thereof and thence into the delivery-tube and out through the primary overflow to the atmosphere. The bore of the forcing steam-jet being of greater sectional area at its smallest point than the

cross-sectional area of the delivery-tube, any excess of steam which cannot find its outlet through the latter will spill at the mouth of the sectional portion 8 of the combining-tube 5 and pass out through the enlargement 9 into the supplementary overflow passage-way. In this way the escaping steam of the forcer will have no retarding influence upon the discharge from the lifter, and in consequence a prompt lifting of the water is effected as well as immediate condensation of the steam in the tubes of the forcer. These tubes being covered by the water within chamber D, such water will flow in the mouth of the portion 7 15 of the combining-tube as the jet of steam and water is established. There being absolutely no surplus steam discharged into the chamber D, the lifter is free to act promptly and furnish the necessary water to the forcer 20 as well as to effect the condensation of the steam in the tubes of the latter. As soon as water is lifted cock E is turned and the auxiliary overflow passage-way (being that of the lifter) is closed, thereby forcing the lifter to 25 drive the water into the forcer combining-tube, there being no other outlet therefor. Then will occur an issue of steam and water through the supplemental overflow leading from the sectional combining-tube of the 30 forcer as well as the primary overflow from the delivery-tube thereof. By now turning the cock still farther and closing the supplemental overflow the only overflow-outlet then left will be the primary outlet from the delivery-tube. The opening to the boiler has 35 by this time been greatly increased by the port d being brought into line between the tubes of the forcer and the boiler-outlet, and the jet being established will enter the boiler 40 with full force. With a still farther slight turning of the cock all communication with the atmosphere is entirely cut off, and the injector will then operate uninterruptedly.

I claim as my invention—

45 1. In a lifting and forcing injector, the forcer combining-tube having a spill-chamber, a supplemental overflow passage-way leading from such chamber, and means for positively closing such passage-way, substantially as set forth.

50 2. In a lifting and forcing injector, the forcer combining-tube formed in sections and having a chamber for receiving the spill of such tube, a supplemental overflow passage-way leading from such chamber, and means for positively closing such passage-way, substantially as set forth.

55 3. In a lifting and forcing injector, the forcer combining-tube formed with a spill-chamber, a supplemental overflow passage-way leading from such chamber, and a cock having a slot designed to coincide with such passage-way, substantially as set forth.

60 4. A lifting and forcing injector having a primary overflow for the forcer, an auxiliary overflow for the lifter, the forcer combining-

tube having a spill-chamber, a supplemental overflow leading from such chamber, and means for closing all of said overflows, substantially as set forth.

70

5. A lifting and forcing injector having a primary overflow for the forcer, an auxiliary overflow for the lifter, the forcer combining-tube having a spill-chamber, a supplemental overflow leading from such chamber, and a single cock having a slot common to all of said overflows, substantially as set forth.

75

6. A lifting and forcing injector having a primary overflow in communication with the delivery-tube of the forcer, and an auxiliary overflow for the lifter, the forcer combining-tube formed in sections, a chamber for receiving the spill from such combining-tube, a supplemental overflow leading from such chamber, and a cock for positively closing all of said overflows, substantially as set forth.

80

7. A lifting and forcing injector, comprising a casing having an overflow-opening, a wall in the discharge-chamber of the lifter extending above the tubes of the forcer, forming an auxiliary overflow passage-way leading to said overflow-opening, the forcer combining-tube having a spill-chamber opening at one end into a passage-way leading to said overflow-opening, and a cock fitted in said overflow-opening and having a slot for coinciding with said passage-ways, substantially as set forth.

85

8. A lifting and forcing injector, comprising a casing, a wall in the discharge-chamber of the lifter extending above the tubes of the forcer, an auxiliary overflow for the lifter on the side of such wall away from the lifter, the combining-tube of the forcer having a spill-chamber, a second wall forming a supplemental overflow leading from said chamber, and means for positively closing both of said overflows, substantially as set forth.

90

9. A lifting and forcing injector, comprising a casing having an overflow-opening extending therethrough, the forcer having a primary overflow in communication with its delivery-tube leading into said overflow-opening and also having its combining-tube provided with a spill-chamber, a supplemental overflow passage-way leading from such chamber into said overflow-opening, and a wall in the discharge-chamber of the lifter extending upwardly therein above the tubes of the forcer and forming an auxiliary overflow passage-way, for the lifter, leading to said overflow-opening, and an operating-cock fitted in said overflow-opening and having a slot designed to coincide with each of said overflows, substantially as set forth.

100

10. In a lifting and forcing injector, the forcer combining-tube formed in sections, one of which has a cylindrical enlargement inclosing the other section, and an overflow passage-way leading from such enlargement, substantially as set forth.

115

11. The combination with the casing hav-

125

130

ing a boiler-outlet, an overflow-opening, the
5 forcer and lifter sets of tubes, and primary,
supplemental and auxiliary overflow pas-
sage-ways leading to said overflow-opening,
of a cock fitted in said overflow-opening hav-
ing two vertical slots either one of which is
designed to coincide with all of said overflow
passage-ways simultaneously, the other slot
being in line with the boiler-outlet, and a
10 large transverse port leading through said

cock in line between the forcer-tubes and
boiler-outlet, substantially as set forth.

In testimony whereof I have signed this
specification in the presence of two subscrib-
ing witnesses.

FRANCIS STICKER.
